CLAIM

The ornamental design for an element of a shoe sole, as shown and described.

DESCRIPTION

FIG. 1 is a lateral side elevational view of an element of a shoe sole showing our new design;

FIG. 2 is a medial side elevational view thereof;

FIG. 3 is a front elevational view thereof; and,
FIG. 4 is a cross section taken along the line 4—4 of FIG. 1.

The broken line showing of a shoe in FIGS. 1-4 is for illustrative purposes only and forms no part of the claimed design.

FIG. 4
